UNITED STATES PATENT OFFICE.

HENRY P. CLAUSEN, OF MAMARONECK, AND CHARLES L. GOODRUM, OF NEW YORK,
N. Y., ASSIGNEES TO WESTERN ELECTRIC COMPANY, INCORPORATED, OF NEW
YORK, N. Y., A CORPORATION OF NEW YORK.

TELEPHONE-EXCHANGE SYSTEM.

Application filed August 24, 1920. Serial No. 405,771.

To all whom it may concern:

Be it known that we, HENRY P. CLAUSEN and CHARLES L. GOODRUM, citizens of the United States, residing at Mamaroneck, in 5 the county of Westchester and State of New York, and at New York, in the county of New York, State of New York, respectively, have invented certain new and useful Improvements in Telephone-Exchange Systems, of which the following is a full, clear, 10 concise, and exact description.

This invention relates to improvements in telephone exchange systems and has particular reference to a circuit arrangement 15 for switches.

In automatic and semi-automatic telephone systems it is customary to provide trunk circuits between different groups of switches and exchanges of a sufficient number to handle the average traffic. During 20 very busy periods, when the traffic exceeds the average, it often occurs that at the particular moment a call is being extended, all trunk circuits are busy, whereas shortly or 25 immediately thereafter one or more of the trunk circuits becomes idle. Systems have been devised in which calls are set upon registers, and in case no trunk circuits are immediately available, the call is held until 30 a trunk circuit becomes idle. In such cases impulses for operating switches to extend the calling line to a called subscriber are always stored up in registers.

The present invention contemplates the 35 provision of means whereby an impulse storing mechanism or register will be utilized only in case all the trunk circuits of a group are busy, the call being normally extended through a switch and over a trunk circuit terminating therein to the exclusion of the 40 impulse storing mechanism. If, however, in extending a call, all trunk circuits of a selected group leading from a particular selector switch are found busy, the selector 45 switch will be held and the impulse storing mechanism will be placed in operative relationship with the impulse sending device. The remaining impulses of the set necessary 50 for extending the calling to the called subscriber are then conveyed to the impulse storing mechanism wherein they are stored. As soon as a trunk circuit becomes idle, the switch is caused to seek such trunk and the impulse storing mechanism is placed in a

condition to deliver its impulses for the 55 purpose of controlling the remaining selector switches of the train.

The inventive idea as involved is capable 60 of receiving a variety of expression. One for the purpose of illustrating the invention is shown in the accompanying drawing; but it is to be expressly understood that such drawing is employed merely for the purpose of facilitating the description of the 65 invention as a whole and not to define the limits thereof, reference being had to the appended claims for this purpose.

In the annexed drawing in which there is 70 illustrated diagrammatically a circuit arrangement and mechanism employed in carrying out the invention, there is shown the station of a calling subscriber 100, a selector switch S, a schematically represented line switch N and an impulse storing mechanism.

It is believed that the invention will be 75 fully understood from the following detailed description of the operation. When a call is initiated by a subscriber removing the receiver from its switchhook at substation 100, a circuit is closed to operate the 80 line switch and to extend the line of the calling subscriber to the selector switch S in a manner well-known in the art. A circuit is then closed for line relay 120 of the selector switch S over a path extending from 85 ground, right-hand winding of relay 120, side-switch arm 121 in its first position, contacts 110 of switch L, conductor 108, terminal 106, brush 103, through the substation loop, brush 104, terminal 107, conductor 109, contacts 111 of switch L, side- 90 switch arm 122 in its first position, and left-hand winding of relay 120 to grounded battery. Relay 120 is thereupon energized and at its armature and front contact establishes a circuit for slow-to-release relay 123. Relay 123 in energizing completes a circuit 95 for relay 198 over a path extending from ground front contact and left hand armature of relay 123 contacts 197, and winding of relay 198 grounded battery. Relay 198 100 in operating locks up through its front contact and armature. The selector is now in condition to receive impulses transmitted from a sending device 101 at the calling 105 sub-station to operate the switch at its primary or group selecting movement. The first deenergization of relay 120 in response

to the impulses establishes a circuit for the second slow-to-release relay 124, extending from grounded battery, winding of relay 124, front contact and right hand armature of slow-to-release relay 123 and back contact armature of relay 120 to ground. Relay 124 being slow-to-release maintains its armature attracted during the transmission of the impulses. The energization of relay 124 establishes a circuit for escape magnet 126 extending from grounded battery, winding of magnet 126, side-switch 125 in position 1 and front contact and armature of slow-to-release relay 124 to ground. Magnet 126 in energizing at this time has no effect upon the side switch mechanism. Each deenergization of relay 120 also closes a circuit for primary stepping magnet 131, traceable from grounded battery, winding of magnet 131, side-switch wiper 130 in position 1, front contact and right hand armature of relay 123 and back contact and armature of slow-to-release relay 120 to ground. Magnet 131 moves brushes 140, 141, 142, and 143 of the switch S in accordance with the impulses transmitted to step said brushes in the group selecting movement. At the termination of the impulses relay 120 remains energized and thus permanently opens a circuit for slow-to-release relay 124 which, after an interval, releases. The deenergization of relay 124 opens the circuit for magnet 126 which thereupon releases and moves the side-switch wipers into position 2. We will assume that one or more trunks of the selected group are idle. In that case no potential will be present on terminal 144. When side-switch wiper 128 moves into its second position, a self interrupting circuit is established for secondary stepping magnet 146, and the brushes 140 to 143 inclusive of the switch S are stepped in a trunk hunting movement over the terminals of the selected group until an idle trunk is found.

At the first energization of secondary magnet 146, the armature of escape magnet 126 is moved to its operative position. If the first trunk of the selected group is busy, ground will be present on test terminal 199 thereof and magnet 126 will be energized over a path extending from grounded battery, winding of escape magnet 126, side switch wiper 125 in its second position, conductor 189, brush 140, to grounded test terminal 199. The escape magnet 126 remains energized as long as brush 140 engages the test terminals of busy trunks. When no ground is found upon a test terminal of the selected group, the escape magnet 126 will release to move the side switch wipers of the selected switch S into their third positions. The calling line is now extended to the next succeeding switch which may be similar to the switch shown. In moving

from position 2 to position 3, the side switch wipers 121 and 122 interrupt the circuit for relay 120 which deenergizes and causes the release of relay 123. This relay is slow-to-release and before it retracts its armatures, the test terminal of the selected trunk is grounded at the succeeding switch due to the energization of a slow-to-release relay corresponding to relay 123, in response to the energization of an impulse relay thereat corresponding to relay 120. This ground causes the trunk to test busy to other testing selectors and operates the relay 150, 151 or 152 associated therewith by attracting its armature closed one break between the terminal 144 and ground. The ground referred to is also extended to the test multiple 105 to hold the line switch set in the well-known manner. This circuit leads over test conductor 189, side switch arm 127 and its third contact, conductor 180, multiple 105, brush 102 to the holding winding (not shown) of the line switch, to battery. This ground is in substitution of the original ground for the holding circuit at the left armature of relay 123. Impulses now transmitted from the sending device 101, will operate the succeeding switch and the extension of a call may continue through other switches until the called line is reached.

At the termination of a conversation, the replacing of the receiver upon the switch hook at substation 100 will cause the ground at the connector to be removed from the release conductor 189 in a manner well known in the art resulting in the release of relay 198. Relay 198 in retracting its armatures completes a circuit for a release magnet 132 over a circuit extending from grounded battery, winding of magnet 132, primary off normal contacts 133 and back contact and outer armature of relay 198 to ground. Magnet 132 operates to restore the switch to normal position whereupon contact 133 is opened and magnet 132 is thus permitted to release.

We will next assume that a call has been extended to selector switch S and that said switch has been operated in its primary selecting movement to select a particular group of trunks and that all trunks in the selected group are busy. In this instance, all relays 150, 151 152 of the selected group will be operated and ground will be present on the test terminal 144 common to said trunks.

A circuit will then be established for relay 134 over path extending from grounded battery, winding of relay 134, secondary off normal contacts 145, side switch arm 129 in its second position, brush 143, terminal 144, and through the front contacts and armatures of relays 150, 151 and 152 in series to ground. Relay 134, in energizing, com-

plete a circuit at its armature and front contact for plunger magnet 160 which in attracting its armature, closes the contacts 112 and 113 and opens the contacts 110 and 111 of the switch L, thereby disconnecting the impulse relay 120 from the calling station 100, and connecting impulse relay 161 thereto. Relay 161 is then energized over a path extending from grounded battery, left-hand winding of relay 161, contacts 112, conductor 108, terminal 106, brush 103 through the substation loop, brush 104, terminal 107, conductor 109, contacts 113 and right-hand winding of relay 161 to ground. Relay 161 in energizing completes a circuit at its armature and front contact for slow-to-release relay 162. Although relay 120 was disconnected from the calling station 100 when magnet 160 was energized, the said relay 120 was not de-energized due to a holding circuit therefore being maintained over a path extending from grounded battery, left-hand winding of relay 120, side switch wiper 122 in its second position, contacts 117 of switch L, contacts 184, 185 and 186, contacts 116 of switch L, side switch wiper 121 in its second position, and right-hand winding of relay 120 to ground. The selector switch S is thus prevented from releasing.

Relay 161 associated with the impulse storing mechanism now responds to impulses transmitted from the sending device 101. The first de-energization of relay 161 in response to the impulses, establishes a circuit for the second slow-to-release relay 163, over a path extending from grounded battery, winding of relay 163, front contact and right-hand armature of slow-to-release relay 162, and back contact and armature of relay 161 to ground. Relay 163 being slow-to-release maintains its armature attracted during the transmission of impulses. Energization of relay 163 establishes a circuit for the escape magnet 170, over a path extending from grounded battery, winding of escape magnet 170, side switch wiper 175, in its first position, and armature and front contact of relay 163 to ground. Magnet 170 in energizing, at this time, has no effect on the side switch mechanism associated with the impulses storing mechanism. Each de-energization of relay 161 also closes a circuit for stepping magnet 165, over path extending from grounded battery, winding of magnet 165, side switch wiper 164 in its first position, front contact and right-hand armature of slow-to-release 162, and back contact and armature of relay 161 to ground.

In response to each impulse, magnet 165 operates pawl 166 to step the impulse wheel 167 in a counter clockwise direction. A spring 220 is fixed to the impulse wheel 167 to tension said wheel when it is moved from normal position so that said

impulse wheel 167 will be restored when the same is released by the holding pawl 168 normally in engagement with a tooth of said impulse wheel. Upon the first step of impulse wheel, contacts 170 are opened and contacts 171 are closed.

At the termination of the series of impulses, relay 161 remains energized and thus permanently opens the circuit for relay 163, which after an interval releases. The deenergization of relay 163 opens the circuit for escape magnet 170 which thereupon releases and moves the side switch arms into position 2.

In the particular arrangement shown, an impulse storing mechanism capable of storing three series of impulses is shown. It is to be understood, however, that the mechanism may be designed to store a greater or less number of series of impulses as desired.

When the side switch arms of the impulse storing mechanism pass into position 2, a circuit is prepared for stepping magnet 175 over a path extending from grounded battery, winding of magnet 175, side switch wiper 164 in its second position, front contact and right-hand armature of relay 162, and back contact and armature of relay 161 to ground. In response to the next series of impulses, stepping magnet 175 may be operated to actuate an impulse wheel similar to 167 in a manner similar to that described for impulse wheel 167. At the termination of the series of impulses, slow-to-release relay 163 will again deenergize thereby opening the circuit for escape magnet 170, resulting in the release of said escape magnet and the passing of the side switch arm into position 3.

In position 3 of the side switch arms, a circuit is prepared for stepping magnet 177 over a path extending from grounded battery, winding of magnet 177, side switch wiper 164 in its third position, front contact and right-hand armature of relay 162, and back contact and armature of relay 161 to ground. In response to the next series of impulses, stepping magnet 177 may be actuated to operate an impulse wheel similar to the impulse wheel 167. At the termination of the set of impulses, escape magnet 170 again deenergizes in the manner heretofore described, and moves the side switch of the impulse storing mechanism into position 4.

It will now be assumed that, during the time that the impulses are being transmitted to the impulse storing mechanism, a trunk circuit in the selected group has become idle. In such case, ground will be removed from the test terminal 144 due to the deenergization of one of the relays 150, 151, 152, opening the circuit to such ground. When no ground is present upon the test terminal 144, relay 184 will retract its armature, thereby

closing the self-interrupting circuit for stepping magnet 146. Stepping magnet 146 then steps the brushes in their trunk hunting movement. Escape magnet 126 of selector switch S, as heretofore described, remains energized as long as the brush 140 of the switch S passes over terminals having ground potential thereon. As soon as an idle trunk is found, escape magnet 126 will deenergize, thereby moving the side switch arms of the selector switch S into third position, whereupon the interrupting circuit for secondary magnet 146 will be opened.

In the third position of the side switch wipers of the selector switch S, a circuit is closed for retaining magnet 195 over a path extending from grounded battery, magnet 195, contacts 171, side switch wiper 174 of the impulse storing mechanism in its fourth position, contacts 118 of switch L, side switch wiper 128 in its third position and back contact and armature of relay 134 to grounded battery. Magnet 195 thereupon attracts its armature thus disengaging pawl 168 from the impulse wheel 167. Under the influence of the spring 220, the impulse wheel 167 is rotated in a clock-wise direction and the teeth thereof operate pawl 169 to open the contacts 184 a number of times corresponding to the impulses previously conveyed thereto, thereby interrupting the loop comprising brush 142, side switch arm 122 in its third position, contact 117 of switch L, contacts 184 and 185 and 186 of the impulse storing mechanism, contacts 116 of switch L, side switch wiper 121 in its third position and brush 141 extending to the succeeding switch. As soon as impulse wheel 167 reaches normal position, a circuit is closed for magnet 176 over a path extending from grounded battery, winding of said magnet, contacts 181, contacts 170, side switch wiper 174 in its fourth position, contacts 118 of switch L, side switch wiper 128 in its third position and back contact and armature of relay 134 to ground. Magnet 176 may attract an armature similar to 168 thereby causing the release of an impulse wheel similar to 167 which, in returning to normal position interrupts the contacts 185 a number of times corresponding to the second set of impulses previously conveyed to the impulse storing mechanism. As soon as the second set of impulses has been delivered magnet 178 will be energized over a path extending from grounded battery, magnet 178, contacts 183, contacts 179, contacts 170, side switch wiper 174 in its fourth position, contacts 118, side switch wiper 128 in its third position and back contact and armature of relay 134 to ground. Relay 178 is thereupon energized and may disengage a pawl similar to 168 from an impulse wheel similar to 167, which wheel upon returning to normal position inter-

rupts the contacts 186 a number of times corresponding to the third set of impulses previously conveyed to the impulse storing mechanism. As soon as the last set of impulses has been delivered the escape magnet 170 is energized over a path extending from grounded battery, winding of magnet 170, side switch wiper 175 in its fourth position, contacts 182, 179 and 170, side switch wiper 174 in its fourth position, contacts 118, side switch arm 128 in its third position, and back contact and armature of relay 134 to ground. Escape magnet 170 is thereupon energized and moves the side switch wipers 175, 164, 173 and 174 of the impulse storing mechanism from position 4 to position 5. Side switch wiper 173 in moving from position 4 to position 5 opens the circuit for relay 160. This relay thereupon retracts its armature thus restoring the switch L to normal position thereby interrupting the circuit for impulse relay 161 and extending the calling station through to the selector switch S. Relay 161, in retracting its armature opens the circuit for a slow-to-release relay 162. Relay 162, in retracting its armature, closes a circuit for reset magnet 171 over a path extending from grounded battery, winding of magnet 171, off-normal contacts 172 and back contact of armature of relay 162 to ground. Magnet 171, in energizing, restores the side switch wipers associated with the impulse storing mechanism to normal position.

At the completion of conversation and restoration of the receiver to the switchboard at station 100, ground will be removed from the test conductor 189 thereby causing the release of relay 198 which in deenergizing closes a circuit for release magnet 132 as previously described thereby causing the restoration of the switch S to normal. Switch S upon reaching normal position causes the release of the non-numerical switch N. The apparatus is then ready for the next call.

What is claimed is:

1. In a telephone exchange system, an automatic switch having trunk terminals arranged in groups, an impulse sender for operating said switch to select a desired group, and means responsive to the busy condition of all the trunks of the selected group for storing impulses.

2. In a telephone exchange system, an automatic switch having trunk terminals arranged in groups, an impulse sender for operating said switch to select a desired group, means responsive to the busy condition of all the trunks of the selected group for storing impulses, means included in the switch for causing the first idle trunk in the selected group to be seized, and means effective when an idle trunk is seized for causing the impulse storing means to transmit the impulses stored therein.

3. In a telephone exchange system, an automatic switch having trunk terminals arranged in groups, an impulse sender for operating said switch to select a particular group of trunks, means responsive to the busy condition of all the trunks of the selected group for storing impulses, means for operating said switch to seek a trunk of the selected group as soon as one becomes idle, and means for actuating said impulse storing means to deliver the stored impulses. 65
4. In a telephone exchange system, a train of switches, each switch in the train having access to a group of trunk circuits, means including an impulse sender for operating said switches in succession whereby each switch prepares to select an idle trunk, an impulse storing mechanism accessible to a particular switch in the train, and means responsive to the busy condition of all the trunks of the group accessible to the particular switch for automatically connecting the impulse storing mechanism in operative relationship with said impulse sender. 70
5. In a telephone exchange system, a calling station, a numerical switch for extending a call therefrom, a group of trunk circuits extending from terminals in said numerical switch to other numerical switches, means including an impulse sender at said calling station for operating said numerical switch to extend said calling station from said switch to a succeeding switch, and means responsive to the busy condition of all the trunks extending from said switch for storing impulses. 75
6. In a telephone exchange system, a calling station, a numerical switch for extending a call therefrom, a group of trunk circuits extending from terminals in said numerical switch to other numerical switches, means including an impulse sender at said calling station for operating said numerical switch to extend said calling station from said switch to a succeeding switch, means responsive to the busy condition of all the trunks of the selected group for storing impulses, means included in the numerical switch for causing the first idle trunk in the selected group to be seized, and means effective when an idle trunk is seized for causing the impulse storing means to transmit the impulses stored therein. 80
7. In a telephone exchange system, an automatic switch, groups of trunk circuits terminating therein, an impulse storing mechanism, an impulse sender for sending a plurality of trains of impulses, one train operating said switch which proceeds to select an idle trunk in the desired group of trunks independently of said impulse storing mechanism if any one of the trunk circuits of the desired group is not busy, and means responsive to the busy condition of all the trunks in the desired group for placing said impulse storing mechanism in operative relationship with said impulse sender to receive the succeeding trains of impulses. 85
8. In a telephone exchange system, a train of automatic switches having primary and secondary movements, a sender for transmitting impulses to said switches, means responsive to impulses for operating one of said switches in its primary movement, means for operating said switch in its secondary movement to select an idle trunk extending therefrom, means for delaying the secondary movement in case all the desired trunks are busy, means at said switch for storing impulses transmitted before the switch has commenced its secondary movement, means for actuating said secondary movement operating means when one of the trunks becomes idle, and means actuated upon the seizure of the trunk to release said impulse storing means to transmit impulses to the succeeding switches. 90
9. In a telephone exchange system, a train of automatic switches having primary and secondary movements, a sender for transmitting impulses to said switches, means responsive to impulses for operating one of said switches in its primary movement, means for operating said switch in its secondary movement, means accessible to said switch for storing impulses transmitted before the switch has commenced its secondary movement, means for delaying the secondary movement and means for releasing said storing means to permit the stored impulses to be transmitted to a succeeding switch. 95
10. In a telephone exchange system, a telephone line, an automatic selecting switch having trunk terminals arranged in groups, an impulse storing mechanism, a sender adapted to set said switch in operative relation to one of said groups, means for thereupon automatically causing said switch to test the trunks of said group, means rendered operative if all the trunks of the selected group are busy for preventing said testing operation from taking place, for holding said switch in its operated condition, and for placing said impulse storing mechanism in operative relationship with said impulse sender, means actuated when a trunk of the group becomes idle for causing said switch to test said trunks, and means actuated when the terminals of an idle trunk are seized for releasing said impulse storing mechanism to permit the stored impulses to be transmitted. 105
- In witness whereof we hereunto subscribe our names this 20th day of August, A. D., 1920. 110
